INVENTOR—

Samuel F. Estell

UNITED STATES PATENT OFFICE.

SAMUEL F. ESTELL, OF CHICAGO, ILLINOIS.

GLOVE AND SHOE BUTTONER.

SPECIFICATION forming part of Letters Patent No. 288,700, dated November 20, 1883.

Application filed September 17, 1883. (No model.)

To all whom it may concern:

Be it known that I, SAMUEL F. ESTELL, of the city of Chicago, county of Cook, and State of Illinois, have invented a new and useful Improvement in Glove and Shoe Buttoners, of which the following is a full and complete description, reference being had to the accompanying drawings.

My invention relates to a buttoner in which the buttoning-hook is adjustably combined with a pencil without interfering with the adjustability of the latter, thus combining two important pocket instruments in one, of convenient size for carrying, and at the same time making the instrument an ornamental article for use at balls or parties where it is usually found desirable to use both buttoner and pencil.

In the drawings, Figure 1 is a view of my invention, showing both the buttoning-loop and pencil in extended positions as in use. Fig. 2 shows both closed. Fig. 3 shows the case with the buttoning-loop removed. Fig. 4 shows the buttoning-loop separated from the case, and Fig. 5 shows the buttoning-loop closed and the pencil extended.

The buttoning-loop is designated as a whole by the letter A.

B represents the tubular case or holder.

30 B' is a slide for securing loop A.

B² represents a pencil made adjustable by the usual screw mechanism.

Loop A is constructed of a single piece of spring-wire bent or formed into the shape shown in Fig. 4, whose buttoning end a a' is so shaped as to be inserted in the button-hole and engage with the button, by which the latter is drawn through and the operation of buttoning performed. The shank of loop A, 35 by which it is secured to case B, is contracted from the swell a to the diameter a², which is equal to the diameter of case B. The flexion of loop A is such that the ends a³, &c., incline outward, as seen in Fig. 4. From a³ said ends

have inward curves a⁴, and terminate with 45 right-line extensions a⁵.

The case B is provided with longitudinal slots b, opposite each other, which have their outward terminations near the end of said case, and extend inwardly to a distance equal to the distance between the points a² and the beginnings of extensions a⁵ of loop A.

To unite loop A with case B, the two portions of its shank are respectively inserted in slots b in such a position that the curves a⁴ 55 rest against the inner ends of slots b with the extensions a⁵ on the interior surface of case B. The shoulders at a² rest against the outer ends of said slots b. The compression necessary to insert the outwardly-inclining ends of the 60 shank is sufficient to measurably hold said shank in place, and the right-line parts thereof, from a² to a³, being embraced by the slots, the loop A is thus partially protected from lateral displacement. The slide B' being brought into 65 position over the shank and slots, loop A is effectually secured in its extended position, as shown in Fig. 1. To close loop A, as shown in Figs. 2 and 5, slide B' is removed and said loop forced in the direction of case B, whereby, 70 by reason of the curvature of shoulders a⁴, the two ends are released from the slots and pass down the cavity of case B until the movement is arrested by the shoulders a², or by the contracted end of said loop, thus shortening the 75 whole into a convenient length for the pocket.

Having thus fully described my said invention, what I claim, and desire to secure by Letters Patent, is—

The article shown and described, consisting 80 of the elastic loop A, slotted case B, and pencil B², substantially as and for the purpose specified.

SAMUEL F. ESTELL.
